UNITED STATES PATENT OFFICE.

CHARLES L. ARCHER, OF MINNEAPOLIS, MINNESOTA.

DESIGN FOR A NON-SKID TIRE-TREAD.

51,429.

Specification for Design.

Patented Oct. 23, 1917.

Application filed August 31, 1917. Serial No. 189,230. Term of patent 7 years.

To all whom it may concern:

Be it known that I, CHARLES L. ARCHER, a citizen of the United States of America, residing at Minneapolis, in the county of Hennepin and State of Minnesota, have invented a new, original, and ornamental Design for a Non-Skid Tire-Tread, of which the following is a specification, reference being had therein to the accompanying drawing.

Figure 1 of the drawing is a perspective

view of a portion of the tire tread showing my new design.

Fig. 2 is a transverse section through the tire showing the sills raised above the face of the tire.

I claim:

The ornamental design for a non-skid tire tread as shown.

In testimony whereof I hereunto affix my signature.

CHARLES L. ARCHER.
